(57) **CLAIM**

The ornamental design for a tissue roll dispenser, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

This application relates to the following design applications being filed concurrently herewith: U.S. patent application Ser. No. 29/242,373, entitled Tissue Roll Dispenser; and U.S. patent application Ser. No. 29/242,371, entitled Tissue Roll Dispenser Cover.

FIG. 1 is a perspective view of the tissue roll dispenser;
FIG. 2 is a top plan view of tissue roll dispenser of FIG. 1;
FIG. 3 a front view in elevation of the tissue roll dispenser of FIG. 1;

FIG. 4 is a right side view in elevation of the tissue roll dispenser of FIG. 1;

FIG. 5 is a rear view in elevation of the tissue roll dispenser of FIG. 1;

FIG. 6 is a left side view in elevation of the tissue roll dispenser of FIG. 1; and,

FIG. 7 is a bottom plan view of the tissue roll dispenser of FIG. 1.

In the drawings textured areas are shown as stippled and polished areas are shown with oblique lines. Preferably, the dispenser is made of a transparent or lightly pigmented material so that the polished areas are relatively transparent and the textured areas are translucent.

Four tissue rolls are shown in dashed lines to illustrate their position in the inventive dispenser when the dispenser is provided with product for dispensing. The rolls form no part of the claimed design.

The area in FIG. 5 within the broken lines on the back of the dispenser forms no part of the claimed design, nor do the broken lines themselves.
